UNITED STATES PATENT OFFICE.

EMIL EFRAN, OF BRÜNN, AUSTRIA-HUNGARY.

FEED-WATER CLEANER AND HEATER.

986,968.

Specification of Letters Patent. Patented Mar. 14, 1911.

Application filed March 16, 1910. Serial No. 549,611.

To all whom it may concern:

Be it known that I, EMIL EFRAN, a subject of the Emperor of Austria-Hungary, residing at Brünn, Austria-Hungary, have 5 invented a new and useful Improvement in Feed-Water Cleaners and Heaters, of which the following is a specification.

My invention relates to steam boilers and especially to cleaning and heating feed 10 water supply for boilers and has for an object, to provide means for separating mud and other impurities from water preparatory to introducing the water into actual contact with the boiler.

15 Another object of the invention is to heat the feed water to such a temperature that the boiler will not be detrimentally affected, as often results from introducing cold water.

I attain the foregoing objects by the 20 mechanism illustrated in the accompanying drawings in which similar reference characters designate similar parts throughout the several views and in which—

Figure 1 is a vertical, longitudinal, sectional view of a device embodying my invention; Fig. 2 is a transverse section through one of the troughs or aqueducts; Fig. 3 is a vertical, longitudinal section through a device embodying a modified 30 form of the device comprising my invention; Fig. 4 is a front elevation of the element "i," of Fig. 3; and Fig. 5 illustrates a vertical transverse section, and a vertical, longitudinal section of another modified 35 form of the device.

The device as illustrated in Fig. 1 is designed to be secured in the steam space of a boiler by any suitable means; its location being such that the member 43 shall always 40 be above maximum high water level. In this figure, "L¹" is the supply pipe through which water or other liquid is introduced; 17, 18, 19, 20 and 21 are chambers for collecting and retaining impurities from the 45 water, and 40, 41, 42 and 43 are aqueducts over which the water passes from one group of chambers to the other group of chambers, and in which heating and evaporation are effected.

50 In operation, water from the pipe L¹ enters the chamber 17 under pressure, and rises to the point indicated by the head of arrow 3; thence, entering the aqueduct 40,

gravitates slowly into the chamber 18. It then rises in chamber 18', through 18'' into 55 the aqueduct 41 and gravitates into chamber 19, and continues thus to flow and rise, following the direction of arrows 7, 8, 9, 10, 11, 12, 13, 14 and 15; finally making exit 60 through the discharge pipe L² into contact 65 with the boiler. Partitions 30, 31, 32, 33 and 34 divide the chamber 17, 18, 19, 20 and 21 respectively, and extend approximately near the bottoms of said chambers to insure that the flow of liquid will not be short circuited near the surface. In making the circuit above described, the water in the aqueducts exposes a large area of surface to contact with the heat and steam in the boiler, and a large area of surface contacts 70 with the aqueducts, which are heated by the steam surrounding them; therefore, the water that flows from the pipe L² is nearly or quite at the temperature of steam, or at the boiling point. It is well known that 75 heating water causes certain solutions therein to coagulate and settle by gravity, and it will be readily understood that if the flow of water be gradual through these aqueducts and chambers, the latter will retain a major 80 part of the sediment, which is detrimental to boilers and that tends to minimize the efficiency thereof.

While I have described my invention as applied to a steam boiler, it may be also 85 applicable in distilleries or other apparatus wherein evaporation, purification or heating of fluid is desirable. My invention is, therefore, not limited to the foregoing disclosure.

I claim:

1. In a liquid heating and cleaning device, a group of chambers, each chamber having a partition therein extending from the top into proximity with the bottom 95 thereof, a second group of chambers of similar construction to first said group, a supply pipe and a discharge pipe communicating with said chambers, and inclined aqueducts connecting the two groups of chambers for 100 the purpose specified.

2. In a liquid heating and cleaning device, a number of groups of chambers, aqueducts connecting the groups of chambers, each chamber having a partition therein, 105 each said partition depending from the aque-

ducts and being spaced apart from the bottom of the chamber, supply and discharge means being connected with said chambers.

3. In a liquid heating and cleaning device, a number of groups of chambers, liquid supply and discharge means connected with the chambers, a partition in each chamber, and an aqueduct connecting a chamber of

one group with a partition of another group of said chambers.

In testimony whereof I have hereunto set my hand in presence of two witnesses.

EMIL EFRAN.
